JOHN C. JEWETT, OF BUFFALO, NEW YORK.

Letters Patent No. 96,923, dated November 16, 1869.

IMPROVEMENT IN WATER-FILTER.

The Schedule referred to in these Letters Patent and making part of the same.

I, JOHN C. JEWETT, of the city of Buffalo, in the county of Erie, and State of New York, have invented certain new and useful Improvements in Water-Filters, of which the following is a specification.

My improvements relate to the employment, in connection with the main filtering-bed, of a subordinate bed, which can be readily removed, and cleansed and refilled, through which the liquid is first passed, the grosser particles of foreign matter being intercepted before reaching the main bed, which can thus be used for years, without change or renovation.

The invention consists—

First, in sinking a vessel in the main and permanent filtering-bed, and arranging therein a removable filtering-cup.

Second, in the arrangement of the cup, forming the subordinate filter, within a larger one, which is sunk in the permanent bed, and provided with perforations, or an escape for the water into the main bed, at or near its upper edge, so that a deposit of a portion of the impurities, which pass through the removable bed, will take place in the bottom of this outer receptacle.

Third, in the employment and arrangement, around the mouth of the removable filter, of a flange, extending above the division-plate, (forming the bottom of the receiving-chamber,) so that the liquid is compelled to pass over the upper edge of this flange or curb, in entering the first filter, whereby the sediment, which is deposited in the bottom of the receiver, is prevented from entering the filter.

In the accompanying drawing, which represents a vertical section of one of my improved filters—

A is the upper or filtering-portion, and

A', the reservoir, beneath, for the filtered water.

The permanent filtering-bed consists of an upper stratum, C, of coarse gravel, with strata C' C'' C''' of charcoal, sand, and fine gravel, successively, beneath.

The composition and arrangement of this bed are old, having been used by me for many years.

D is the receiving-chamber, into which the water is first poured.

E is the sunken cup, soldered or otherwise fastened at its upper edge to the division-plate f, and

e e are the perforations near its upper edge, for the escape of the water into the main bed.

G is a smaller cup, filled with gravel or other filtering-material, suspended within the cup E by means of a flange at its upper edge, overlapping the edges of the hole in the division-plate, so as to leave a space around and below it and the cup E, as shown.

m is the flange, surrounding the mouth of this lesser filter, and

n is a sponge, placed within this curb or collar, and resting on top of the gravel.

The sponge may be held in place by a perforated cap, s, which may be made to screw over the flange m, as represented.

The vessel E may be made to extend downward, so as to be soldered to the bottom plate of the main bed, as required.

The operation of my improvements is as follows:

The water being poured in the receiver D, a partial deposit first takes place at its bottom. The sponge and gravel in the cup G will remove the grosser particles of the foreign matter contained in the water, which passes through the perforated bottom of the cup, into the outer cup, at the bottom of which a further deposit takes place.

From the top of this vessel the water flows through the perforations, into the permanent bed, through which it filters into the reservoir A', beneath.

The cup G can be removed from time to time, as it becomes foul, by unscrewing the cap s, which leaves the cup and its contents free to be taken out. The deposit in the bottom of the vessel E can now be removed, and the cup G and sponge, after being refilled and cleansed, replaced.

It is evident, that by means of my improvement, the greater portion of the impurities will be deposited or intercepted, in the bottom of the receiver, in the cup G, or in the bottom of the vessel E, so that the permanent filtering-bed can be used a long time, before it will require to be changed.

What I claim, as my invention, is—

1. The arrangement of a removable filtering-cup, G, within a vessel, E, sunk in the permanent filtering-bed, substantially as set forth.

2. With a removable filtering-cup, G, embedded vessel E, and permanent bed of a filter, arranged as hereinbefore described, the outlet e, arranged near the top of the vessel E, as and for the purpose set forth.

3. The arrangement, with the division-plate f and removable filter, of the curb or flange m, in the manner and for the purpose specified.

JNO. C. JEWETT.
